UNITED STATES PATENT OFFICE.

WILLIAM D. STANCIL AND JOHN H. NUNNELEE, OF DONIPHAN, MISSOURI.

HANDLE-FASTENING MEANS.

No. 843,970.

Specification of Letters Patent.

Patented Feb. 12, 1907.

Application filed March 19, 1906. Serial No. 306,811.

To all whom it may concern:

Be it known that we, WILLIAM D. STANCIL and JOHN H. NUNNELEE, residing at Doniphan, in the county of Ripley and State of Missouri, have invented a new and useful Improvement in Handle-Fastening Means, of which the following is a specification.

Our invention is in the nature of an improved means for detachably connecting a handle to a hoe, rake, gig, spade, or kindred implements, and it primarily seeks to provide a means of the character stated of a simple and economical construction which can be readily applied or detached and will effectively serve its intended purpose.

Generically our invention comprehends a socket having means for interlocking with the handle portion fitted thereon and a special construction on the said handle whereby the same when secured by the socket-locking means is adapted to coöperate with a threaded extension on the implement to be attached to effect a secondary locking of the handle for holding it from working out of its primary locking position.

In its more subordinate features our invention consists in certain details of construction and combination of parts, all of which will be hereinafter fully described, pointed out in the appended claims, and illustrated in the accompanying drawings, in which—

Figure 1 is a perspective view of a garden-hoe and handle with our improved fastener means applied. Fig. 2 is a longitudinal section of the hoe-shank, the fastener devices, and the socket-engaging end of the handle. Fig. 3 is a cross-section on the line 3 3 on Fig. 2. Fig. 4 is a perspective view, partly in section, of the socket member. Fig. 5 is a similar view of the socket-engaging end of the handle. Fig. 6 is a detail view which illustrates the relative positions of one of the socket-locking lugs and the coacting locking-groove in the handle before the handle is shifted by the shouldered tang 3, and Fig. 7 illustrates the said parts adjusted to the supplemental interlocking position. Fig. 8 is a cross-section taken on the line 8 8 on Fig. 2.

In the practical application of our invention we provide a socket member 1, of the usual external shape, the lower end of which has a longitudinal threaded aperture 2 to receive the threaded end 30, formed in the tang or shank 3 of the hoe, shovel, gig, or other implement which it is desired to detachably, but rigidly, attach to handle, and the said tang

has its end extended beyond the threaded portion 30 and terminates in a smooth finger 31 of reduced diameter whereby to provide a shoulder 32 at the ends of the threaded portion of the tang, the reasons for which will presently appear.

The socket member 1 on its inner wall at one side has a pair of inwardly-projected lugs 10 10, and on the opposite side intermediate the lugs 10 it has a single lug 11, and these lugs are arranged to interlock with a pair of bayonet-joint locking-grooves 12 and 13 on the lower end of the handle that extend lengthwise of the handle from the lower end thereof, the groove 12 being the shorter one and having its upper end merging with the transverse groove-section 12^a, that forms the locking-groove portion as it turns over the single lug 11 on the socket.

The groove 13, which is the longer groove, merges with two lateral groove portions 13^a 13^b, adapted to turn over the two locking-lugs 10 10 on the socket, and the lower end of the handle has a central longitudinally-extended socket 14, the lower end of which is reinforced by the apertured face-plate 15, as shown.

Each of the lateral or lug-receiving portions of the grooves 12 and 13 has at its throat an upwardly-projecting lug or shoulder *a a*, and the said portions are of greater width than the locking-lugs on the socket, whereby when the handle has been adjusted to bring the socket-lugs 10 and 11 to seat in the said socket portions a slight movement backward of the handle in the longitudinal plane will cause the lugs 10 and 11 to engage the lower edges of the groove portions 12^a and 13^a, and thereby bring the socket-lugs 10 with their lower edges in a plane below the shoulders or lugs *a a*, which thereby locks the handle from turning within the socket 1 so long as the handle remains forced outward to bring the lugs *a a* in position to project beyond the lower ends of the socket-lugs, and to provide for thus holding the handle the socket is screwed down onto the threaded shank of the hoe or other implement until the smooth projected end of the shank fits 105 the socket in the lower end of the handle, and by screwing the socket further the shoulder on the threaded shank engages the handle and forces it longitudinally upward in the socket until the lower edges of the socket-lugs seat on the lower edge of the lateral groove portions of the handle in a plane be-

low the shoulders at the throat of such groove portions, which operation provides for a supplemental locking of the handle within the socket since it holds the handle from being rotated and turned with the long grooves in alignment with the socket-lugs.

5 To maintain the socket and handle at the supplemental locked position, as indicated, a jam-nut 4 is fitted on the threaded shank or 10 tang of the hoe-blade, as shown.

To detach the handle, it is only necessary to turn back the jam-nut and to turn the handle with the socket to unscrew the socket sufficiently to permit of shoving the lower 15 end of the handle inwardly until the shoulders or stops on the lateral grooves are sufficiently below the socket-lugs (see Fig. 6) to allow the handle to be turned with the long 20 grooves in line with said lugs when it (the handle) can be readily pulled out.

Having thus described our invention, what we claim is—

1. A fastener device of the character described, comprising a socket having a means 25 for interlocking with the handle, a threaded shank adjustably mounted in the socket having a portion adapted to engage the handle whereby to shift it and hold it to its locked engagement with the socket.

30 2. In a fastener means of the character stated, a socket having a member for interlocking with the handle, a threaded aperture in its outer end and a threaded implement carrying shank movable in the socket aperture and adapted to engage and clamp the handle whereby to fixedly hold it interlocked with the socket, as set forth.

35 3. The combination with the socket having a threaded aperture in its lower end, a handle, a socket having an internal lug and a handle having a longitudinal groove, a transverse groove that merges with the longitudi-

nal groove, and provided with shoulders at the mouth of the transverse groove; of a threaded shank movable in the threaded portion of the socket, adapted to engage the handle whereby to shift it in the socket, substantially as shown and described.

4. The hereinbefore-described improvement in handle-fastener means, which comprises in combination a socket having a threaded aperture in its lower end and a longitudinal locking-lug, a threaded shank movable through the threaded aperture in the socket, said shank having a reduced end and a shoulder at such end, and a handle having a longitudinal groove and a transverse groove that merges with the longitudinal groove, said transverse groove having a seat portion at the forward side, said handle also having a socket at its front end to receive the forward end of the shank and a jam-nut on the shank, all being arranged substantially as shown and described whereby when the handle is turned so its transverse groove receives the socket-lug, the fitting in of the shank will shift the handle to bring the socket-lug to engage the seat in the transverse groove in the handle, for the purposes described.

5. The combination with a handle having a bayonet-groove, and a socket having a lug to interlock with the bayonet-groove in the handle, said socket also having a threaded aperture in its end; of a threaded shank for engaging with said aperture and the lower end of the handle and means for holding the shank to its adjusted positions, as set forth.
